EMERGENCY DAMPER CONTROL

Bearl E. Colburn and Lee Colburn,
Green Bay, Wis.

Application June 2, 1949, Serial No. 96,795

12 Claims. (Cl. 74—2)

1

Our invention relates to improvements in emergency damper controls.

Heating devices, such as furnaces and other fuel burning units relying upon air supply and the adjustment of quantity of air supply for their control, even though provided with automatic devices for the adjustment of dampers, check drafts, and draft doors, offer a distinct fire hazard in the event that the operator forgets to retard the fire, or in the event that the automatic device fails, for lack of power, or fails due to mechanical disability. It is the object of our invention to provide an emergency control, supplemental to either a hand-operated or automatically-operated air feed control for furnaces or heaters, whereby, in the event of an overrun of temperature, to shut off air feed or otherwise to check combustion.

More specifically stated, it is the object of our invention to provide a thermostatically responsive device which will assure return of damper, draft doors, or checks to fire retarding position if temperature exceeds a safe control value.

Another object of our invention is to provide a thermostatically releasable emergency link for a conventional control of a furnace draft.

In the drawings:

Fig. 1 is a perspective of our emergency draft damper control, showing our emergency releasable strip chain in normal, or standby position, in readiness for an emergency release.

Fig. 2 is a side elevation of a conventional warm air furnace with our control in position for draft door release.

Fig. 3 shows our invention installed on a conventional warm air furnace in position for check damper release.

Fig. 4 is a longitudinal vertical section through our emergency control.

Fig. 5 is a section on line 5—5 of Fig. 4.

Fig. 6 is a section on line 6—6 of Fig. 5.

Fig. 7 is a detail of our emergency trip chain and illustrating its mode of releasable attachment to the operating arm of our control.

Like parts are designated by the same reference character throughout the several views.

Conventionally, draft doors 10 for furnaces 11, and check dampers 12 for such furnaces are controlled by control chains 13 in a well-known manner, either by connection to manually operated devices, or to automatically controlled devices which raise and lower the chains to alter the position of a draft or check.

Draft door 10 or check damper 12 will either close of its own weight, as shown in Fig. 2, or a

special weight, as shown at 14 may be used to assure that the damper will assume a safe position if the chain 13 is released. If, however, due to power failure of an automatic damper control device or to forgetfulness of the operator of a manually controlled furnace, the damper or check is left in position for rapid combustion of fuel in the furnace, a dangerous condition may develop. We, therefore, provide our emergency draft damper control now to be described.

Our draft damper control includes an instrument housing 15 on a back plate 16 which may be secured by suitable sheet metal screws or otherwise to the casing of a furnace 11 as shown clearly in Figures 2 and 3. Extending forwardly from a side wall of the instrument housing 15, is a free floating lever 17 which may oscillate freely about the shank 18 of a slotted thimble 19 mounted in a boss 20 forming a part of the side wall of the housing 15. Control chain 13 is connected near the outer end of lever 17 and we provide a control chain 25 from the lever 17 to the damper 10 or check 12.

At 26 the arm 17 is provided with a spool apertured at 27 to freely receive a special, bead type trip chain 28. This forms an emergency link between the chain 25 and a release ring 30 receivable in slotted thimble 19. So long as the release ring is held in the slot in the thimble 19, chain 13 and the chain 25 act as one continuous pull chain element so that the automatic or manual device used to adjust these chains and the position of the dampers to which they are connected will be substantially in accord with conventional practice. Dampers and draft doors are often quite heavy, and it is for this reason that we provide pin 29 projecting from arm 17 at a point spaced from the spool and somewhat below a straight line drawn between the trip rod and the spool. Release of the ring 30 under emergency conditions and the use of pin 29 will be described below.

When the ring is released, the weighted damper pulling downwardly upon chain 25 will pull the free running trip chain 28 through spool 26 until the ring 30 strikes the spool. This will in effect add some chain to the effective length of the chain 25 and permit the damper or check to close.

Extending rearwardly from the back plate 16 into the bonnet of furnace 11 is a thermostatic device including a mounting tube 31, a helically wound bi-metallic element 32 and a thermostatically controlled rod 33 which extends centrally of the tube 31 into the instrument housing

15 where the end of the thermostatically controlled rod 31 is provided with a trip flange 34. Tube 31 is guided in collar 35 welded or otherwise secured to the back plate 16, and the tube may be oscillated in the collar by means of a temperature setting lever 36, which is rigidly secured to a tube collar 37 fixed upon inner end of the tube 31 as shown clearly in Figures 1, 4 and 5. Temperature setting lever 36 extends through the top of the instrument housing 15 and is disposed in front of calibrations marked on the back plate and will therefore indicate the temperature setting of thermostat 32, since one end of the bi-metal helix is secured to the tube at 38 and the other end of the helix is secured at 39 to rod 33.

It will be clear from this description that upon movement of the temperature setting lever 36 the tube 31 is oscillated so as to change the position of the point of attachment of the helix 32 at 38. This point of attachment is the reference point from which the helix operates and therefore determines the temperature at which our emergency control is to operate.

In Figure 6 it will be noted that slot 40 extends substantially beyond the axis of shank 18 of the thimble and that the shank 18 is bored at 41 to loosely receive trip rod 42, which extends retractably transversely of the slot 40 and transversely of the interior of the instrument case. The trip rod is provided with a shoulder flange 43 and a knurled extension 44 to protrude from the instrument case on the side opposite thimble 19. Reset spring 45 between the side of the instrument case and the shoulder flange 43 of trip rod 42 constantly urges the trip rod toward the left as seen in Figures 5 and 6.

Extending from collar 34 on rod 33 is a trip lever 46, which is in position to oscillate against shoulder flange 43 of trip rod 42 in opposition to the thrust of spring 45 when the temperature of thermostatic element 32 increases so as to provide increased torque.

When trip lever 46 does not interfere, spring 45 thrusts rod 42 into position across the slot 40 so that it may extend through release ring 30 and retain it in position during normal operation of the furnace.

It will now be clear that so long as the trip rod 42 is in position to retain the release ring 30 the furnace controls applied to chain lever 17 and chain 25 will operate in the conventional manner to raise and lower chain 13 to open and close any drafts or dampers connected thereto. Throughout such normal operation the arm 17 will oscillate freely without affecting any of the mechanism in the instrument housing 15, and release ring 30 will oscillate freely about the trip rod 42.

If, however, the temperature of the thermostatic element 32 which extends into the bonnet of the furnace 11, exceeds the temperature for which arm 36 has been set, the trip lever 46 oscillated by the thermostatic action upon helix 32 and rod 33 will bear against shoulder 43 to compress spring 45 and retract trip rod 42 from slot 40. When this occurs, release ring 30 is released by trip rod 42 and the freely running bead chain 28 will slip through spool 26 so as to add a number of inches to the effective length of chains 25 and 13, thus permitting the damper or check to close of its own weight.

To set our emergency draft damper control the release ring and the chain 28 may be manually pulled back into the position shown in Figures 1,

5, and 7, while the knurled reset extension 44 is pulled outwardly of the housing 15, against the compression of spring 45. Then while the release ring is held in position, the trip rod 42 will be permitted to assume the position in Figure 5 under the thrust of spring 45. Obviously this cannot be done while the trip lever 46 is in a position dictated by a high temperature in the furnace bonnet, but will ordinarily be done after the fire in the furnace has been damped by our emergency release of the chain 28.

It will be noted that we have made provision for adjustment of the critical release point of our control, since arm 36 and tube 31 to which it is attached constitute the reference point from which the helix 32 operates. If there is need to recalibrate the thermostatic device, we provide a screw at 47 through collar 37 to bear against the tube 31. This set screw may be released and a different setting of the collar 37 and arm 36 with reference to the tube may be determined. Then when the set screw 47 is again tightened a new reference point for the thermostat 32 will have been obtained and the temperature setting at which the trip arm 46 will effectively withdraw the trip rod 42 can be accurately set by moving the temperature setting lever 36.

Obviously chain arrangements between our emergency draft damper control and the actual draft door 10 may be direct as shown in Figure 2, or it may follow devious paths over pulleys 41, 43, to check 12 as shown in Figure 3.

We referred above to the fact that a heavy draft door might cause trouble in the operation of the release ring 30. Since friction induced between rod 42 and the ring may be considerable, pin 29 is so positioned that trip chain 28 may be drawn beneath it and the pin will then be disposed between two of the beak like links. The person resetting our emergency damper control can pull the trip chain far enough toward the trip rod 42 so that some slack may be provided in the length of trip chain extending from pin 29 to the release ring 30. In fact, then, the trip chain is "snubbed" around the pin 29 and will remain in this position to take some of the strain off of the slack and of the trip chain, thus reducing the friction between trip rod 42 and the ring 30 when an emergency release trip operation is to be accomplished.

In the operation the release ring is held firmly in the slot 40 by the trip rod 42, until the temperature of the bimetallic helix 32 is raised to the critical degree to which the temperature setting lever 36 has been set. As the temperature increases the trip lever 46 is oscillated to the right (counterclockwise) as seen in Fig. 5, and the trip rod 42 is thrust to the right against the pressure of spring 45. Finally the ring 30 is released by the trip rod so that the trip chain 28 slides through spool 26. Thus, when the ring 30 strikes the spool the length of the trip chain 28 has been added to the controlled chain 25 and this is sufficient to permit the damper 10 or check 12 to close.

When the fire has been damped sufficiently to cool the thermal responsive helix 32 our emergency damper control may be manually reset. The trip lever will have moved clockwise to a position permitting the spring to thrust trip rod 42 to the left (Fig. 5), and the trip rod can be withdrawn to the right, manually, while ring 30 is inserted in the slot 40. Trip rod 42 may then be manually released, to be "laced" through the ring. Our emergency damper control is then set for an

automatic release, should an emergency high temperature condition again be reached.

From the above description it will be seen that our emergency draft damper control provides an effective release of an emergency trip chain 28 in chains 13-25 to shut down furnace operation in the event that excessive temperatures develop in a furnace. Many of the automatic furnace controls now on the market are equipped with thermostatic devices known as "limit" controls by means of which it may be predetermined that the automatic temperature control of the furnace will shut down the furnace drafts or other combustion promoting means at a predetermined high temperature. Such predetermined high temperature might be 300 degrees in the bonnet of the furnace 11, and our emergency draft control thermostat 32 would then be set at a somewhat higher temperature, as for instance, 325 degrees. If the furnace temperature then exceeded the normal 300 degree "limit," this indicating that the ordinary automatic control had failed, the trip lever 46 would, at 325 degrees, withdraw the trip rod 42 and release ring 30 for an emergency shut down of the dampers.

We claim:

1. In a device of the character described a swingable member having a fixed pivotal mounting and a floating end, a pair of control linkage members extending respectively to and from the floating end of said member whereby to additively provide control linkage of a normal control length, emergency linkage disposed in releasably retained position parallel to the swingable member and connected to one of said pair of control linkage members whereby upon release of the emergency linkage its length is added to said normal control length.

2. The device of claim 1 wherein the swingable member is provided with an apertured spool at its floating end through which the emergency linkage is freely movable and one end of the emergency linkage is provided with a release ring too large to pass through the spool.

3. An emergency damper control having a housing providing bearings for a pair of rods disposed at right angles to each other; one of the rods having a thermally responsive member for oscillation of the rod and the other rod being a shouldered trip rod reciprocable in its bearings; a bearing for one end of the trip rod comprising a shanked and slotted thimble; an arm freely rotatable on the shank of the thimble and provided with a control chain to move the arm; a spool on the arm spaced from the thimble; a controlled chain disposed over the spool and provided with a release ring disposable in the slot in the thimble whereby to be releasably retained by the trip rod; and a trip arm connected to the thermally responsive rod in position to bear upon the trip rod and withdraw it from the release ring.

4. An emergency damper control having a housing providing bearings for a pair of rods disposed at right angles to each other; one of the rods having a thermally responsive member for oscillation of the rod and the other rod being a shouldered trip rod reciprocable in its bearings; a bearing for one end of the trip rod comprising a shanked and slotted thimble; an arm freely rotatable on the shank of the thimble and provided with a control chain to move the arm; a spool on the arm spaced from the thimble; a controlled chain disposed over the spool and provided with a release ring disposable in the slot in the thimble

whereby to be releasably retained by the trip rod; a trip arm connected to the thermally responsive rod in position to bear upon the trip rod and withdraw it from the release ring; and a spring between the housing and the shoulder on the trip rod to urge said rod to ring retaining position.

5. A damper control connection extending from a damper to a point of control, a movable member at the point of control provided with releasable attaching means attached to the damper control connection, a spool on the movable member spaced from the releasable attaching means over which spool the damper control connection may move when released and a snubbing pin fixed to said movable member and about which the said control connection is snubbed between the spool and the releasable attaching means.

6. A damper control connection extending from a damper to a point of control, a movable member at the point of control, said movable member being provided with a fixed pivotal mounting, releasable attaching means adjacent said pivot and to which the damper control connection is releasably attached, a spool on the movable member spaced from the releasable attaching means and over which spool the damper control connection may move when released and a snubbing pin for said control connection between the spool and the releasable attaching means and thermostatic means having a trip for releasing the releasable attaching means.

7. In a device of a character described, a supporting housing provided with a slotted thimble having a bored shank, a trip rod reciprocable in the bore in said shank and extending across the slot, a thermostatically responsive member positioned to bear against the trip rod, and a damper control trip chain having a release ring receivable in the slot for engagement by the trip rod, a free floating lever mounted upon the shank of the thimble, and a spool on the lever mounted at a point spaced from the trip rod for passage of the trip chain and retention of the ring.

8. A swingable emergency control arm for a two-part tension connection for a damper, said arm being swingable about a fixed center, one of said parts of the tension connection being directly connected to a swingable outlying portion of said arm, the other of said parts being releasably connected adjacent the center and held approximately parallel to the arm by a pulley-like spool adjacent said outlying portion of the arm, and a thermally responsive tripping device adjacent said center to release said other part of the two-part connection whereby to lengthen the tension connection.

9. The control of claim 8 wherein the spool is shaped to retain the released end of said other part.

10. An emergency damper control comprising a support, thermally responsive trigger mechanism mounted on said support, an arm pivotally connected to said support, portions of the arm remote from the pivot being provided with connections for control linkages to a damper and connections for control linkages to a damper control, said control linkages being in series and said arm being normally oscillatable about its pivot without materially altering the combined lengths of the said control linkages, one of said control linkage connections comprising an apertured spool on the arm, and a releasable coupling connected with said trigger mechanism and to which coupling one of said control linkages is at-

tached; said one control linkage extending to said coupling through said spool aperture and along said arm, the thermal response of said trigger mechanism being effective to release the coupling and said one control linkage for movement along the arm whereby to increase the effective combined length of said linkages.

11. The device of claim 10 wherein said one linkage has a stop portion engageable with said spool whereby to limit the increase of the combined lengths of said control linkages upon actuation of the trigger mechanism.

12. The device of claim 11 wherein said thermally responsive trigger mechanism comprises members mounted for relative movement and thermally responsive means for causing such relative movement, one of said members having

5 motion transmitting connection with said releasable coupling and the other of said members being provided with means for adjusting said mechanism to be responsive to a selected temperature.
